UNITED STATES PATENT OFFICE.

LEVI STEVENS, OF WASHINGTON, DISTRICT OF COLUMBIA.

IMPROVEMENT IN BUOY-LIGHTS.

Specification forming part of Letters Patent No. 125,096, dated March 26, 1872.

SPECIFICATION.

To all whom it may concern:

Be it known that I, LEVI STEVENS, of the city of Washington, in the District of Columbia, have invented certain Improvements in Buoy-Lights, of which the following is a specification, reference being had to the accompanying drawing:

My invention consists in the novel construction of a petroleum-vapor burner and sea-buoy, for the purpose of burning the vapor under pressure, and providing the buoy with a steady brilliant light to indicate its locality.

In the drawing, Figure 1 is a perspective view of my combined sea-buoy and vapor-burner, with a portion of the buoy broken away, showing its interior; and Fig. 2 is a longitudinal vertical section of the burner and a portion of the device for retorting and supplying the gas or vapor to the burner.

The want of some reliable device by which the location of buoys might be indicated or made known in dark nights or in foggy, cloudy, or stormy weather, has long been felt. To meet this want is the object of this invention.

A tank, A, made out of any suitable material, and of any size or form desired, is used for the buoy, and also for holding the material for supplying the burner with its gas or vapor. Into the upper end of this tank is inserted a pipe or tube, B, so that its lower end will extend nearly to the bottom of the same. At its upper end is attached, so as to communicate with it, a hollow elliptical-shaped ring, D. From each end of this ring extend downward hollow arms C, which enter and are connected to a body, E. The pipe B, ring D, and arms C are all hollow, and are filled with fine copper wire, arranged compactly therein. The lower ends of the arms C enter a chamber, a, within the body E. Above this chamber is another chamber, b, but separated from it by a partition, c. In the partition c is a small opening, which may be partially or entirely closed by means of a needle-valve, F, the stem of which screws into the body E, as clearly shown in Fig. 2, so as to be operated by thumb-piece G, as shown in Fig. 1. Over the chamber b is placed the burner H, the upper end of which is made flat and flaring, and so as to throw the

flame within and against the ring D. The pipe B is furnished with a stop-cock, I. In operating this device the tank is first supplied with petroleum, then with bicarbonate of soda, and afterward with some sulphuric acid. The action of the acid upon the soda produces carbonic-acid gas, which in turn presses upon the petroleum and forces it up through the pipe B. The cock I is now opened and heat is applied to the pipe, ring D, and arms C, which is communicated to the copper wire within them. The wire thus heated retorts or converts the oil into a vapor, which passes into the body E, thence through the opening in the partition c into the chamber b, and thence through a small opening in the upper side of this chamber to the burner. The object of the chamber b is to have the vapor supplied to the burner in a steady continuous stream, which would not be the case if it came directly from the needle-valve opening in the partition C. As the vapor comes from the burner it is lighted, and the heat produced by its combustion keeps the copper wire hot, and the process of retorting the oil and supplying the vapor continuous.

In each side of the burner are the usual openings for supplying air or oxygen to the flame.

In this way, it will be seen, not only is a buoy provided, but also one that, by means of the material within it and the vapor-burner attached to it, is supplied with a steady and brilliant light whenever desired—a light that, with the ordinary protection, will continue to burn in the roughest weather, and thus furnish the object so much desired by navigators, an illuminated buoy.

Having thus described my invention, what I claim is—

A buoy-light, consisting of a petroleum-vapor burner in combination with a hollow buoy, the former being supplied with petroleum or oil under pressure from the latter, in the manner substantially as herein described.

LEVI STEVENS.
